Primary Examiner — Cynthia Ramirez*(74) Attorney, Agent, or Firm* — Gerald R. Black, Esq.(57) **CLAIM**

The ornamental design for a vehicle stanchion loading with a mounting bracket, as shown and described.

DESCRIPTION

FIG. 1 is a perspective view of a vehicle stanchion for loading with mounting bracket showing my new design; FIG. 2 is another perspective view thereof;

FIG. 3 is a top view thereof;

FIG. 4 is a bottom view thereof;

FIG. 5 is a left side view thereof;

FIG. 6 is a front view thereof;

FIG. 7 is a right side view thereof; and,

FIG. 8 is a rear view thereof.

The broken line showing in FIG. 2 is included for the purpose of illustrating environment and forms no part of the claimed design.
